SIGNAL TRANSMITTING APPARATUS

Louis Girardin, Paris, France, assignor, by mesne assignments, to The Union Switch & Signal Company, Swissvale, Pa., a corporation of Pennsylvania

Application September 26, 1936, Serial No. 102,774
In France April 10, 1936

4 Claims. (Cl. 177—380)

This invention relates to signal transmitting apparatus particularly in connection with railway and other signaling systems, and has for its chief object to provide an improved system by means of which a signal or indication may be given on vehicles or cars of any kind more particularly locomotives or cars on railways.

The advantage of such a system will be obvious particularly in connection with the giving, on a moving vehicle, of indications of the necessity to modify the speed, or for automatically modifying the speed by actuation of the accelerating or braking apparatus, when the vehicle approaches shunting yards, curves, cross-overs or points.

The railway or other signaling system according to the present invention is characterized in that there are supplied to the signaling circuit current impulses comprising a code the pattern of which is determined in accordance with the operation of a group of sequentially controlled devices such, for example, as a counting relay chain.

The signal transmitting apparatus set forth in my present application is somewhat similar to that set forth in the copending application of Lloyd V. Lewis, Serial No. 600,786, filed on March 23, 1932 for Remote control systems, and the said copending application contains claims which cover broadly certain features of the invention described in my present application.

In order that this invention may be the more clearly understood and readily carried into effect, we will proceed to describe the same with reference to the accompanying drawings, which illustrate by way of example and not of limitation certain convenient arrangements according to the present invention for controlling the usual signaling devices used for producing current variations in the signaling circuits, and in which

Figure 1 is a diagrammatic representation of a simple coding or modulating device for producing current variations.

Fig. 2 is a diagrammatic representation of a signaling system according to the present invention showing means for modifying the code produced by the device shown in Fig. 1.

Fig. 3 is a diagrammatic time-table showing the sequence of operations of the apparatus shown in Fig. 2.

Referring now to Figure 1, the signaling circuit C shown therein comprises a single track section which is insulated from the other track sections in accordance with the usual practice in the so-called "automatic block" installations.

The two rails are connected to the ends of the secondary windings of a transformer 1, the primary winding of which is connected to a source of alternating current (not shown) at DE. In the primary circuit of the transformer 1 there is included a switch 2 and a current interrupting device 3 controlled by a modulator or coder 4 which may be of any suitable form such, for example, as a special relay, an oscillating circuit with or without a thermionic valve, a rotary contactor, a vibrating device or a chronographic pulsator or the like. The said modulator is connected through a switch 5 to a suitable source of current or to a suitable controlling system (not shown) at the points A and B.

The operation of this system is as follows:—when the switches 2 and 5 are closed the modulator 4 is brought into operation and alternately makes and breaks the primary circuit of the transformer 1 by means of the interrupting device 3, thereby causing corresponding current variations or impulses to be induced in the secondary circuit and in the signaling circuit C. It will be obvious that when a vehicle or train equipped with suitable receiving apparatus enters the track section it will receive the variations thus produced to give the desired indications or to effect the necessary vehicle control.

The arrangement above described by way of example is, of course, only a simple form and it will be obvious that such an arrangement may be associated with suitable track circuit apparatus used to actuate wayside signals thereby giving a wayside signal indication in addition to the indication obtained on the vehicle. The above-mentioned circuits may also be used to control the actuation of the switches 2 and 5, for example, so that they are closed only on the approach of a vehicle. It is also possible to provide suitable emergency or auxiliary devices with a view to obviating a failure of the feeding source or of the devices which are normally provided. Moreover, if desired, several coding devices such as 4 may be provided and may be combined in such a way that one or more of these can be used to produce the rail current codes or variations.

In Figure 2, in which like reference characters refer to similar parts, the apparatus of Figure 1 is shown combined, in accordance with this invention, with apparatus for modifying the code produced by coder 4. For this purpose the coder 4 is provided, in addition to the interrupting device 3, with two interrupters 6 and 7 capable of being brought alternately into contact with the respective contacts 8 and 9. It will be apparent

that when the device 3 is in one of its contact positions, contact finger 6 will engage the upper contact 8 and contact finger 7 will be out of contact with the lower contact 9 while, when the device 3 is in its other contact position, contact finger 6 will be out of contact with the contact 8 and contact finger 7 will make contact with the lower contact 9.

One terminal B of the supply system, which in the example shown is a source of direct current, is connected to the coder 4 and to the supply wires of several suitable relays 10, 11, 12, 13, 14, and 15, respectively, which comprise a counting chain, the operation and function of which will be described hereinafter. With the relays of this chain are respectively associated the contacts 10a, 10b, etc., 11a, 11b, etc., the numeral designating each contact indicating the relay with which it is associated and the suffix indicating the particular contact in question. The apparatus includes also two control relays 16 and 17 having a time constant such that these relays both remain energized during the normal sequential operation of the counting chain. Relays 16 and 17 are arranged in such a manner that relay 16 is controlled by the even-numbered relays (10, 12, 14) while relay 17 is controlled by the odd-numbered relays (11, 13, 15). The operation of the apparatus is indicated diagrammatically in the time-table of Fig. 3 and is as follows:—Assume first that all of the relays 10 to 17 are de-energized and that the coder 4 is brought into action through closing of the switch 5 in the circuit A, 5, 4, B. This will bring the finger 6 into contact with contact 8 for the first impulse whereupon the following pickup circuit will be established for relay 10: A, 6, 8, 16a, 17a, 10, B. As soon as relay 10 picks up, it will remain energized during the time contact 6—8 remains closed over the following stick circuit: A, 6, 8, 11a down, 10a up, 10, B. Pickup of relay 10 closes the following pickup circuit for the checking relay 17: A, 6, 8, 11c, 13c, 15c, 17, 10d, B. As soon as relay 17 picks up, it establishes an obvious stick circuit for itself over contact 17b. During the operation so far described, contact 6—8 has remained closed. As soon as contact 6—8 opens, and contact 7—9 closes for the second impulse, energy is removed from relay 10 but this relay remains picked up for a short interval thereafter sufficient to enable relay 11 to pick up over the following circuit: A, 7, 9, 15b, 10b, 11, B. Relay 11 will now pick up and will prepare a pickup circuit for relay 12 over front contact 11a. When relay 11 picks up, the circuit for relay 10 which was previously interrupted at contact 6—8 is interrupted at a second point, namely at back contact 11a. Pickup of relay 11 closes the following pickup circuit for the checking relay 16: A, 7, 9, 14c, 12c, 10c 16, 11d, B. As soon as relay 16 picks up, it closes an obvious stick circuit for itself over its front contact 16b. The pickup of relay 16 completes the circuit for the primary of transformer 1 over contacts 3, 16c, 11e, and 17c so that an impulse is transmitted to the track.

During the time that the contact 6—8 remains open, energy is removed from relay 17, and during the time contact 7—9 is open, energy is likewise removed from relay 16. The release time of these relays is sufficiently long, however, to bridge these open circuit intervals so that in the normal sequential operation of the counting chain, both relays 16 and 17 remain picked up.

It will be apparent that if the cycle of opera-

tions had begun for that position of coder 4 in which finger 7 makes contact with contact 9, then no relay of the counting chain would have been energized. The cycle of operations must, therefore, always begin with the energization of the first relay 10 of the series. The checking relays 16 and 17 will both remain picked up as long as proper sequential operation of the counting relays continues, but should a failure occur in such sequential operation, one or the other of these relays will release and will introduce a tell-tale interruption in the code being supplied to the track circuit C. That is, if any one of the counting relays 10 to 15 should fail to release within the required time as determined by the slow release interval of its associated checking relay, the latter relay will release and will not pick up again until the apparatus is restored to its inactive condition in which all of the counting and checking relays are deenergized. This is because the pickup circuits for relays 17 and 16 include a front contact 10d or 11d of the respective relay 10 or 11 and neither of these relays can be picked up until the pickup circuit over back contacts 16a and 17a is established for relay 10 to start the counting cycle. Relay 16 will be released by a prolonged open circuit interval at one of the contacts 10c, 12c, or 14c, whereas relay 17 will be released by a similar prolonged opening at one of the contacts 11c, 13c, or 15c.

When contact 6—8 closes at the third impulse of the code cycle (relay 11 being energized and relay 10 being deenergized during the operation hereinbefore described) the following pickup circuit for relay 12 will be established: A, 6, 8, 10a down, 11a up, 12, and B. An obvious stick circuit for relay 12 will be established over contact 13a down and contact 12a up as soon as relay 12 picks up. Meanwhile, relay 11 will release due to opening of its stick circuit at contact 7—9 as well as at back contact 12a. It will be apparent, therefore, that at the third impulse, relay 12 will be picked up and relays 10 and 11 will both be released. In the operation so far described, relay 10 was picked up by the first impulse, relay 11 by the second (which released relay 10), and relay 12 by the third (which released relay 11).

In a similar manner which will be entirely clear from the foregoing description, relays 13, 14, and 15 will be picked up by the fourth, fifth, and sixth impulses, respectively. It will be clear, therefore, that the group of relays 10, 12, and 14 respond sequentially to the odd-numbered impulses and the group of relays 11, 13, and 15 respond sequentially to the even-numbered impulses of the series within each code cycle.

At the first impulse of the succeeding code cycle (relay 15 having been picked up during the sixth impulse of the previous cycle) the following pickup circuit for relay 10 will be established: A, 6, 8, 14a down, 15a up, 10, and B. From this point on, the operation for succeeding impulses is identical with that already described and will be clear without added description.

In the normal operation of the system, as soon as relays 17 and 16 pick up, impulses will be transmitted to the track circuit alternately over the upper and lower fingers of interrupter 3 controlled by the coder 4 and operating in synchronism with the fingers 6 and 7 which control the counting chain. The number of such impulses depends on the number of counting relays which have a front contact (10e, 11e, 12d, 13d) included in the code supply circuit. It is understood, of course, that since no impulses can be transmitted

until both checking relays 16 and 17 are picked up, the full number of impulses will not be transmitted until after the initial starting cycle of the apparatus has been completed. In the example illustrated, relays 10, 11, 12, and 13 each have a contact in the code supply circuit so that once relays 16 and 17 are both picked up, the first four impulses of the code cycle will be transmitted to the track circuit, whereas the last two impulses will be blanked out. The supply circuit may be traced as follows: E, 17c, any one of the contacts 10e, 11e, 12d, or 13d (in definite sequential order), 16c, upper or lower finger of interrupter 3, primary winding of transformer 1, 2, and D.

Obviously, any other suitable number of impulses could be selected for transmission to the track circuit.

I claim:

- 20 1. In a signaling system, in combination, a signaling circuit, a source of current, a code transmitter for coding the current from said source in accordance with a predetermined pattern, a chain of counting relays controlled by said code transmitter in such manner as normally to be operated and released in sequence one at a time, means controlled by said counting chain for recurrently modifying the pattern of said current, a slow acting relay for checking the sequential 25 operation of said counting chain, said slow acting relay having a retardation sufficient to bridge the normal operation time of a counting relay of said chain, a pickup circuit for said slow acting relay including a contact of said code transmitter and back contacts of said counting relays; a holding circuit for said slow acting relay including said slow acting relay for impressing the resulting current on said signaling circuit.
- 20 2. In a signaling system, in combination, a signaling circuit, a source of current, a code transmitter for periodically coding the current from said source, a supply circuit for impressing said coded current on said signaling circuit, a chain of counting relays controlled by said code transmitter in such manner as normally to be operated and released in sequence one at a time, means controlled by said counting chain and included in said supply circuit for introducing a periodic interruption in said coded current, a checking relay for checking the sequential operation of said counting chain and having a contact included in said supply circuit, said checking relay having a retardation sufficient to bridge the normal operation time of a counting relay of said chain, a pickup circuit for said checking relay including a contact of said code transmitter and back contacts of said counting relays, and a holding circuit for said checking relay including said

code transmitter contact, said back contacts and a front contact of said checking relay.

3. In a signaling system, in combination, a code transmitter for producing constantly recurring series of substantially uniform current impulses, a signaling circuit to receive said impulses, a chain of counting relays controlled by said code transmitter in such manner as normally to be operated and released in sequence one at a time for registering sequentially all of the impulses of said series, a checking relay for checking the sequential operation of said counting chain, said checking relay having a retardation sufficient to bridge the normal operation time of a counting relay of said chain, a pickup circuit for said checking relay including a contact of said code transmitter and back contacts of said counting relays; a holding circuit for said checking relay including said code transmitter contact, said back contacts, and a front contact of said checking relay; and means controlled by said counting chain and by said checking relay for transmitting a selected number of said impulses to said signaling circuit.

4. In a signaling system, in combination, a code transmitter for producing constantly recurring series of substantially uniform current impulses, a signaling circuit to receive said impulses, a chain of counting relays controlled by said code transmitter in such manner as normally to be operated and released in sequence one at a time for registering sequentially all of the impulses of said series, said counting chain comprising a first relay group for registering the odd-numbered impulses of said series and a second relay group for registering the even-numbered impulses of said series, a first checking relay for checking the sequential operation of said first relay group, a second checking relay for checking the sequential operation of said second relay group, said first and said second checking relays each having a retardation sufficient to bridge the normal operation time of a counting relay of the respective relay group, a pickup circuit for said first checking relay including a normal contact of said code transmitter and back contacts of said first relay group; a holding circuit for said first checking relay including said normal contact, said back contacts and a front contact of said first checking relay; a pickup circuit for said second checking relay including a reverse contact of said code transmitter and back contacts of said second relay group; a holding circuit for said second checking relay including said reverse contact, said back contacts of the second relay group, and a front contact of said second checking relay; and means controlled by said counting chain and by both of said checking relays for transmitting a selected number of said impulses to said signaling circuit.

LOUIS GIRARDIN.
